UNITED STATES PATENT OFFICE.

SAMPSON W. MOON, OF CHICAGO, ILLINOIS.

ELECTRIC SAFETY-RAZOR.

1,072,634.

Specification of Letters Patent.

Patented Sept. 9, 1913.

Application filed October 4, 1909. Serial No. 520,835.

To all whom it may concern:

Be it known that I, SAMPSON W. Moon, a citizen of the United States of America, and resident of Chicago, Illinois, have invented a certain new and useful Improvement 5 in Electric Safety-Razors, of which the following is a specification.

My invention relates to improvements in razors of the safety type, and has for its 10 object the production of a device in which electricity is used to actuate the razor head and blade from side to side during its use.

A further object is the production of improved means for actuating the razor head 15 and blade so as to provide the most efficient stroke.

A further object is the production of a device of simple construction, positive in its operation, and one that is least liable to 20 get out of order.

These and such other objects as may hereinafter appear are attained by my device, embodiments of which are illustrated in the accompanying drawings, in which—

25 Figure 1 represents a front elevation of my device. Fig. 2 represents a side elevation of my device partly in section, with the razor and head removed. Fig. 3 represents a front elevation of my device partly 30 in section, with wires removed and with the razor and head in position.

Like numerals of reference indicate like parts in the several figures of the drawings.

Referring now to the drawings: 4 represents 35 the outer tubular casing serving as a handle, and open at its lower end and provided with a small opening 5 in its upper end. A tubular support 6 fits within the lower end of the casing and is provided 40 with a circumferential flange 7 fitting snugly against the lower edge of the casing. An insulating collar 8 fits within an opening in the center of the end of the support 6, permitting the passing of wires within the 45 support.

Mounted on the inside of the support 6 by any suitable means—as, for instance, rivets—is a spring 9 on which is mounted a supporting bar or frame 10. This bar is 50 turned upwardly at its upper end, and a razor stem 11 mounted thereon. Mounted on the upper surface of the bar 10 near its lower end are two posts provided with contact screws 14—15, and an electro-magnet 55 (shown as two coils 16—16^a) is mounted on the bar. The spring armature 17 is mount-

ed on the post 13 at a suitable distance above the magnet contacts 18, and at its upper end is provided with a hammer or striker 19 having on its striking face a rubber buffer 20. The stem 11 passes through the opening 5, and is preferably screw-threaded at its end, and a razor frame handle 22 is screwed thereon. On this handle is mounted an ordinary safety razor 65 frame 23 within which is fitted a razor blade 24.

The device is connected with a source of electric power, for instance a pair of dry cells (not shown), the circuit being through 70 cord 29 to post 13, to armature spring 28, and through cord 30 to coil 16^a, connecting wire 31 to coil 16, cord 32 to post 12 and contact spring 26. A switch (not shown) is conveniently located to turn the current on 75 and off. In order to prevent the admission of water within the casing when cleaning the razor, the razor handle 22 at its lower end is flared outwardly, forming a circumferential flange. This serves to deflect the 80 water running down the handle and prevents it from passing within the opening 5.

The device may be used on the ordinary electric light circuit, or any other source, by placing a suitable resistance (not shown) in 85 the circuit to prevent the burning out of the coils 16 and 16^a. It will thus be seen that as the current passes through the coils the armature is attracted, forcing the striker 19 against the bar 10. By means of the make-and-break device above described, the armature is vibrated rapidly, the striker 19 striking against the bar with each vibration, thus transmitting the vibration to the stem 11 and through it to the razor frame carrying 90 the razor blade. These vibrations are, of course, lengthwise of the blade, so that as the razor is drawn over the face during shaving, the frame and blade are moving rapidly sidewise, giving a saw effect and aiding materially in the cutting of the beard. In the 95 use of the ordinary safety razor the hair of the beard is cut by a direct pull, and the operation is often very unsatisfactory, especially if the beard happens to be stiff or the razor dull. By the use of my device, however, the sidewise movement of the razor blade, moving with the frame, performs the cutting operation, the razor being drawn lightly over the face. It will be noted that, 100 as the beard is not cut by a direct pull, the blade has to simply move slowly over the

face in order to bring the moving blade against the hairs of the beard and the disagreeable pulling of the beard is entirely done away with and the user relieved from 5 the necessity of exercising any special care or skill in the manipulation of the razor.

As the coils, posts, contact spring and armature are all mounted on the bar and the bar attached to the support back of the 10 device, the entire structure vibrates when the device is in operation and the contact spring is not affected in any way by changes in pressure on the razor frame. This being the case no amount of pressure on the razor 15 head can affect the operation of the device.

While I have shown an improved form of construction, it is evident that various modifications can be adopted without departing from the spirit of my invention.

20 I claim:

1. An electric safety razor, comprising a handle, a razor frame, a blade mounted thereon, and electrical means for vibrating said razor frame and blade, said means comprising an electro-magnet, an armature adapted to vibrate independently of said razor frame, and means for imparting said vibrations to the razor frame and blade.

25 2. An electric safety razor, comprising a casing, a razor frame, a razor blade mounted thereon, an electro-magnet, an armature, a striker mounted on said armature, means for vibrating said armature, and means for transmitting the vibrations of said armature striker to said razor frame and blade.

30 3. An electric safety razor, comprising a casing, a razor frame, a razor blade mounted thereon, an electro-magnet, an armature, a striker mounted on said armature, an inter-

rupter in the circuit of said electro-magnet 40 to vary the energization of said magnet to thereby vibrate said armature, and a bar adapted to be struck by said striker for transmitting the vibrations of said armature striker to said razor frame and blade.

45 4. An electric safety razor comprising a casing, a supporting bar, a razor frame, a razor blade mounted thereon, an electro-magnet and armature seated on said bar, a striker mounted on said armature, an electric circuit breaker arranged to operate said armature whereby said striker engages said bar to thereby transmit the vibrations of said armature striker to said razor frame and blade.

50 5. An electric safety razor, comprising a supporting bar, a razor frame and an electro-magnet rigid with said bar, a spring mounted armature adapted to vibrate independently of said bar, and means for imparting the vibrations of the armature to the supporting bar and razor frame.

55 6. An electric safety razor, comprising a razor frame, an electromagnet and a supporting bar for said frame and magnet, a spring mounted armature for said electromagnet adapted to vibrate independently of said razor frame, and a striker attached to said armature adapted to strike said supporting bar whereby the razor frame may be 60 70 vibrated by the operation of said armature.

Signed by me at Chicago, Illinois, this 24th day of September 1909.

SAMPSON W. MOON.
